UNITED STATES PATENT OFFICE.

JOSEPH OLIN BENNETT, OF SHREVEPORT, LOUISIANA.

POST FOR WELL-DRILLING ROTARIES.

1,418,056.

Specification of Letters Patent. Patented May 30, 1922.

Application filed March 16, 1920. Serial No. 364,706.

To all whom it may concern:

Be it known that I, JOSEPH OLIN BENNETT, a citizen of the United States, and a resident of Shreveport, in the parish of 5 Caddo and State of Louisiana, have invented certain new and useful Improvements in Posts for Well-Drilling Rotaries, of which the following is a specification.

My invention is an improvement in posts, 10 and has for its object to provide a post of the type designated "back-up posts" for rotary drilling rigs for drilling wells, wherein in the post is so arranged that it is not necessary to remove the same when taking 15 off the tongs, the post consisting of hinged sections, one of which is adapted to swing on the other, releasable means being provided for holding the movable section in alinement with the body of the post.

20 In the drawings:

Figure 1 is a side view of the improved post, showing the parts locked;

Figure 2 is a front view showing the parts loosened and in inoperative position;

25 Figure 3 is a top plan view of Figure 2.

In the present embodiment of the invention the improved post comprises a lower section 1, which is adapted to be seated in a hole or otherwise supported, and a section 2 which is hinged to the section 1. The section 1 has a pair of laterally spaced lugs 3 at its upper end, between which is received a lug 4 on the lower end of the section 2, and a bolt 5 is passed through registering openings in the lugs to pivotally connect the parts, the belt being engaged by a nut 6.

Referring to Figure 1, it will be seen that the section 1 has a head 7 at its upper end 40 from which the lugs 3 extend, and a handle, indicated at 8, is pivotally connected with the lower section of the post at this point. This handle has connected with one end thereof a yoke comprising a body 9 and 45 arms 10, the yoke body being connected to the handle, while the arms 10 extend on opposite sides of the head 7, and the said arms are pivotally connected to the head by a bolt and nut 11. At the end of each 50 arm remote from the handle there is provided a lateral extension or lug 12 and these lugs or extensions are adapted to engage on opposite sides of the lugs 3 and 4, when said lugs are in alinement, as clearly shown

in Figure 1, to hold the section 2 of the 55 post in vertical position and in alinement with the section 1. When the handle is swung downwardly, as shown in full lines in Figure 1, these lugs 12 will lie across the three lugs 3 and 4, while when the handle 60 is swung up into the dotted line position of Figure 1 the extensions 12 release the lug 4 so that the post 2 may swing down into the position shown in Figures 2 and 3.

In operation, to set up the post, it is only 65 necessary to swing up the section 2 and to permit the handle 8 to drop. The engagement of the body of the yoke with the section 1 of the post limits the downward movement of the handle to the position of Figure 70 1, wherein the lugs 12 are in operative position. When it is desired to release the movable section, the handle is lifted, as shown in dotted lines in Figure 1. The lug 4 is now released, and may swing into the position of Figures 2 and 3. These posts are 75 used for holding chain tongs when breaking joints in pipe, and with the improved post the post may be tripped and the tongs taken out without taking the post out of the hole 80 or other holder for the same.

Figure 1 illustrates the sectional post in its operative position and it also illustrates a wrench 18 in its operative position in engagement with the upper section 2 and in 85 engagement with the joint 19 of a string of pipe 20. When the wrench is in this position, the contact of the wrench handle with the section 2 will prevent the rotation or swinging of the wrench handle beyond 90 the section 2. When the joint has been broken, the operator may grasp the lever or handle 8 and elevate the same so that the upper section assumes the full line position illustrated in Figure 2. When the upper 95 section 2 is thus positioned the wrench may be rotated slightly and easily released from the joint 19.

With reference to the foregoing description, it will be seen that the upper section 100 2 may be readily swung to its lower position by simply elevating the handle 8, whereupon the wrench may be readily swung around and released. By the use of this form of post, much labor will be saved and 105 the breakage usually occurring when the wrench and the break-out pin are pounded for releasing the wrench, is eliminated.

Figure 1 illustrates the lower section 1 of the post as being rotatably carried by the platform 22 of the rotary.

I claim:

- 5 1. A post of the character specified comprising a lower section and an upper section, said sections having interengaging lugs and a pivotal connection between the lugs, releasable means, normally operative, connected with the lower section for engaging the lugs to hold the sections in alinement, said means comprising a lever pivoted to the lower section, and having extensions adapted to extend across the lugs when the 10 posts are in alinement, to prevent the breaking of the joint.
- 10 2. A post of the character specified comprising a lower section and an upper section, said sections having interengaging lugs and a pivotal connection between the lugs, 20 and releasable means normally operative, connected with the lower section for engag-

ing the lugs to hold the sections in alinement.

3. A device of the character specified comprising post sections, one of the sections having a pair of longitudinally extending lugs at one end and the other having a single lug fitting between the first named lugs, a pivotal connection between the lugs, 30 and a handle having connected therewith a yoke, the arms of the yoke engaging opposite sides of the first named section adjacent to the lugs and being pivoted to the said section, each arm of the yoke having a 35 lateral extension adapted to extend across the lugs when the sections are in alinement, the body of the yoke being adapted to engage the lower section when the handle swings downwardly to hold said extensions 40 in position to prevent movement of the sections.

JOSEPH OLIN BENNETT.
